6 Claims. (Cl. 81—17.2)

1

The invention relates to a vise with pneumatic or hydraulic operation of the movable jaw which is displaceable in a longitudinal guide.

Vises of this kind are already known. However, it has been found that such a vise is suitable only for the finishing or the assembling of work pieces or the like in mass production but is unsuitable in the case of manufacture of single articles, for which purpose an ordinary manually operated vise is required. A further disadvantage of the known vises is that they are, from the outset, constructed for operation by compressed air and that the reconstruction of the known manually operated vises into vises which render operation by compressed air possible is practically impossible.

The present invention has set itself the problem of providing a vise which obviates the aforesaid disadvantages. This problem is, according to the invention, solved by connecting the movable jaw with a casing which is intended for receiving and for discharging the pressure medium and which is displaceable, for the purpose of moving the jaw, by means of a piston that is mounted on a spindle, which, in turn, is in operative connection with a manually rotatable spindle sleeve that is provided for operating the jaw.

A further feature of the vise according to the invention consists in arranging, on the casing, an adjustable and fixable member which is intended for co-operation with the spindle and for fixing the distance to be traversed by the jaw under the action of the pressure medium.

According to the invention, the casing is detachably connected with the jaw by means of a part of the casing which surrounds a part of the spindle, which part of the casing carries a guiding member which is intended for the straight guiding of the casing when it is being displaced by means of the piston or for the straight guiding of the spindle during the manual operation and which engages in a longitudinal groove in the spindle part.

In a preferred embodiment of the vise, the piston is acted upon by a spring which is stressed during the displacement of the jaw to its operative position and which effects the return of the jaw to its inoperative position. However, the casing may also be provided at each end with an inlet and an outlet for the pressure medium for the purpose of selectively displacing the casing with the connected jaw to the clamping position or to the inoperative position of the latter.

2

The vise according to the invention is, owing to the ease with which it is operated by hand or by means of a pressure medium, suitable both for manufacturing or machining single articles and for carrying out series work, in the latter case the operation by pressure medium being extraordinarily rapidly effective, being adjustable to a high pressing pressure, and considerable saving of time on clamping and unclamping the work pieces being rendered possible.

The vise may be constructed together with the pressure-medium operating device as a single unit. However, the pressure-medium operating device may also be made as a separate unit which can, after a few alterations, be fitted to an existing manually operated vise.

An example of embodiment of the subject matter of the invention is represented in the accompanying drawings, of which

Fig. 1 shows the vise partly in elevation and partly in longitudinal section, the jaws being shown in the position in which the work piece is released.

Fig. 2 is a longitudinal section through the part which serves for displacing the movable jaw and which is shown with the jaw in the clamping position.

Fig. 3 is a longitudinal section, on an enlarged scale, showing a detail of the movable jaw and its guide means; and

Fig. 4 is a cross section along line IV—IV of Fig. 3.

The vise represented comprises a vise body 1, with a device for clamping it to a bench 22 or the like, and a stationary jaw 2. Horizontal support part 1b of the vise body carries slide guide 3, in which the movable jaw 4 is displaceably mounted by means of guide rib 4a. Wedge member 23 is interposed between bench 22 and support part 1b so that the cylinder casing 13 may be above the plane of the bench. In the body 1 and beneath the stationary jaw 2 there is mounted, rotatably but not axially displaceably, a spindle sleeve 5, one end of which carries a tommy-bar 6 whilst the other end, which has a smaller internal diameter, is provided with an internal screw-thread 7. Screwed into the end of the sleeve 5 which has the internal screw-thread is a screw spindle 8 which is connected with a spindle 10 by means of a cross pin 9. The spindle 10 has a longitudinal groove 11 extending over a part of its length and is mounted, so as to be longitudinally displaceable, in a bore in a part 12 of a casing 13. Part 12 is provided with radial bore 12a to

facilitate the insertion of pin 9 to connect spindles 8 and 10.

Fixed on the end of the spindle 10 that extends into the casing 13 is a piston 14, acting upon which is a helical spring 16 which, at one end, rests on the lid 15 of the casing. Arranged on the lid 15 of the casing is a set screw 12 which is accessible from the outside and can be fixed in position by means of a check nut 17 and is arranged coaxially with the spindle 10 and at an adjustable distance from the end of the latter. In the casing 13, at the end opposite the lid 15, there are two bores 19 and 20 which are provided with screw-threads and both of which open into the space in the casing behind the piston 14. One of these bores, for example the bore 19, communicates with a source of compressed air for introducing compressed air into the casing 13, a valve (not shown), which is adapted to be operated by hand or foot, being connected in front of the casing. The second bore, namely the bore 20, communicates with, for example, an outlet valve (also not shown), which is adapted to be operated by hand or foot. The cylindrical part 12 of the casing has, on its end that has a reduced diameter, an external screw-thread which is screwed into an internal screw-thread in a bore in the rear end of the movable jaw 4. Instead of the screw connection, there may be another known detachable or fixed connection between these parts.

The operation of the apparatus described is as follows:

By rotating the sleeve 5 by means of the tommy-bar 6, the screw spindle 8 is moved into the sleeve 5 or in the opposite direction according to the direction of rotation. Since the screw spindle 8 is connected with the spindle 10 by the pin 9, the spindle 10 follows the movement of the screw spindle 8, the piston 14 carrying out, by means of the casing 13, a movement of the movable jaw 4 toward the stationary jaw 2 when the spindles 8 and 10 are displaced to the left in Fig. 1. On the other hand, if the spindles 8 and 10 are displaced to the right in Fig. 1, the helical spring 16 causes a corresponding movement or displacement of the casing 13, and the movable jaw 4 is moved away from the stationary jaw 2. The spindles 8 and 10 and the casing 13 together with the connected movable jaw consequently continue to maintain their mutual position during the rotation of the sleeve 5, a rotation of the spindle 10 and, consequently, also of the screw spindle 8 about the common axis being impossible owing to the longitudinal guiding of the movable jaw 4 and the engagement of the guiding screw 21 in the longitudinal groove 11 in the spindle 10.

The distance of the movable jaw 4 from the stationary jaw 2 can consequently be adjusted by hand in such a manner that the work piece to be clamped can be inserted between the two jaws with more or less clearance. If compressed air is then admitted into the casing 13 through the bore 19, it effects, with compression of the helical spring 16, the spindles 8 and 10 being stationary, a displacement of the casing 13 to the left in Fig. 1 or to the position shown in Fig. 2. This straight-line longitudinal movement, which is due to the engagement of the guiding screws 21 in the longitudinal groove 11, is transmitted to the movable jaw 4 which bears on the work piece with a clamping pressure that is dependent upon the quantity of compressed air admitted into the casing 13. The distance to be

traversed by the movable jaw in order to clamp a work piece can be fixed at the outset to a definite amount by means of the set screw 18, this distance being dependent upon the distance of the jaw from the end of the spindle 10. If the set screw 18 is screwed into contact with the spindle 10, only an operation of the movable jaw 4 by hand is possible. This possibility of adjusting the distance by means of the set screw 18 has, especially in the clamping of a large number of like work pieces in succession in the same vise, the advantage that the pressing pressure is the same with all the work pieces and limits the quantity of compressed air admitted into the casing 13.

In order to remove the work piece from the vise, it is only necessary to operate the outlet valve connected with the bore 19 in the casing. To the extent to which the compressed air escapes from the casing 13, the spring 16 presses the casing 13 and, with it, the movable jaw 4 back to its initial position shown in Fig. 1.

In the embodiment represented, there are provided two spindles 8 and 10 which are coupled together by a pin 9 and which can be replaced by one spindle made of a piece of metal and which has a screw-thread over a part of its length. Instead of using compressed air as the agent for moving the movable jaw, a pressure liquid may be employed. Also, the compression spring 16 employed for returning the movable jaw to its initial position for the purpose of releasing the clamped work piece could be dispensed with if, for example, the bore 20 is shifted to the opposite end of the casing and known controlling means are provided which render it possible to supply the pressure medium, i. e., compressed air or pressure liquid, alternately to one end and the other of the casing, the pressure medium, which is no longer intended for performing work as regards the movement of the casing by means of the piston, being pushed out by the latter.

What I claim is:

1. A vise comprising a longitudinally displaceable jaw operable by fluid pressure, a casing connected to said jaw for unitary movement therewith and adapted for receiving and discharging pressure fluid, a piston in said casing, said pressure fluid reacting on said piston, for displacing said casing and thereby moving said jaw, a spindle on which said piston is mounted, a manually rotatable spindle sleeve operatively connected to said spindle to operate said jaw, said casing comprising a part detachably connected to said jaw and surrounding a part of said spindle, said part of said spindle having a longitudinal groove therein, and a guiding member carried by said casing part and engaging said longitudinal groove for the straight guiding of said casing during its displacement.

2. A vise comprising a longitudinally displaceable jaw operable by fluid pressure, a casing connected to said jaw for unitary movement therewith and adapted for receiving and discharging pressure fluid, a piston in said casing, said pressure fluid reacting on said piston for displacing said casing and thereby moving said jaw, a spindle on which said piston is mounted, a manually rotatable spindle sleeve operatively connected to said spindle to operate said jaw, said casing comprising a part detachably connected to said jaw and surrounding a part of said spindle, said part of said spindle having a longitudinal groove therein, and a guiding member carried by said casing part and engaging said longitudinal groove

for the straight guiding of said spindle on the manual operation of said spindle sleeve.

3. A vise comprising a longitudinally displaceable jaw operable by fluid pressure, a casing connected to said jaw for unitary movement therewith and adapted for receiving and discharging pressure fluid, a piston in said casing, said pressure fluid reacting on said piston for displacing said casing and thereby moving said jaw, a spindle on which said piston is mounted, a manually rotatable spindle sleeve operatively connected to said spindle to operate said jaw, an adjustable and fixable member arranged on said casing to co-operate with said spindle to fix the maximum distance to be traversed by said jaw under the action of said pressure fluid, said casing comprising a part detachably connected to said jaw and surrounding a part of said spindle, said part of said spindle having a longitudinal groove therein, and a guiding member carried by said casing part and engaging said longitudinal groove for the straight guiding of said casing during its displacement.

4. A vise comprising a longitudinally displaceable jaw operable by fluid pressure, a casing connected to said jaw for unitary movement therewith and adapted for receiving and discharging pressure fluid, a piston in said casing, said pressure fluid reacting on said piston for displacing said casing and thereby moving said jaw, a spindle on which said piston is mounted, a manually rotatable spindle sleeve operatively connected to said spindle to operate said jaw, an adjustable and fixable member arranged on said casing to co-operate with said spindle to fix the maximum distance to be traversed by said jaw under the action of said pressure fluid, said casing comprising a part detachably connected to said jaw and surrounding a part of said spindle, said part of said spindle having a longitudinal groove therein, and a guiding member carried by said casing part and engaging said longitudinal groove for the straight guiding of said spindle on the manual operation of said spindle sleeve.

5. A vise comprising a longitudinally displaceable jaw operable by fluid pressure, a casing connected to said jaw for unitary movement therewith and adapted for receiving and discharging

pressure fluid, a piston in said casing, said pressure fluid reacting on said piston for displacing said casing and thereby moving said jaw, a spindle on which said piston is mounted, a manually rotatable spindle sleeve operatively connected to said spindle to operate said jaw, a spring acting upon said piston and stressed on the displacement of said jaw to the operative position and effecting the return of said jaw to its inoperative position, said casing comprising a part detachably connected to said jaw and surrounding a part of said spindle, said part of said spindle having a longitudinal groove therein, and a guiding member carried by said casing part and engaging said longitudinal groove for the straight guiding of said casing during its displacement.

6. A vise comprising a longitudinally displaceable jaw operable by fluid pressure, a casing connected to said jaw for unitary movement therewith and adapted for receiving and discharging pressure fluid, a piston in said casing, said pressure fluid reacting on said piston for displacing said casing and thereby moving said jaw, a spindle on which said piston is mounted, a manually rotatable spindle sleeve operatively connected to said spindle to operate said jaw, a spring acting upon said piston and stressed on the displacement of said jaw to the operative position and effecting the return of said jaw to its inoperative position, said casing comprising a part detachably connected to said jaw and surrounding a part of said spindle, said part of said spindle having a longitudinal groove therein, and a guiding member carried by said casing part and engaging said longitudinal groove for the straight guiding of said spindle on the manual operation of said spindle sleeve.
